United States Patent Office.

AMBROSE TOWER, OF NEW YORK, N. Y.

Letters Patent No. 96,511, dated November 2, 1869.

IMPROVEMENT IN CLOTHES-WRINGERS.

The Schedule referred to in these Letters Patent and making part of the same.

To whom it may concern:

Be it known that I, AMBROSE TOWER, of New York city, in the county of New York, and State of New York, have invented a new and valuable Improvement in Clothes-Wringers; and I do hereby declare that the following is a full, clear, and exact description of the construction and operation of the same, reference being had to the annexed drawings, making a part of this specification, and to the letters and figures of reference marked thereon.

Figure 1, of the drawings, is a top plan view of my invention.

Figure 2 is a longitudinal sectional view of the same.

My invention relates to means for washing and wringing clothes; and

It consists mainly in a novel arrangement of devices, intended to serve an efficient purpose in such washing and wringing.

The letter A, of the drawings, represents a wash-board constructed in the ordinary form, except that its sides are lengthened at their tops to serve the purpose of a frame for the wringing-apparatus hereinafter described.

The letters c represent hooks attached to the wash-board, and which are intended to clasp over the top of one side of a wash-tub, to hold the board in place while the washing and wringing-process is being carried on.

The letters D represent two rubber rollers, arranged as wringers. One of these rollers works in bearings upon the upper side of the wash-board, and the other has its bearings upon the lower side thereof, their rela-

tive position to each other being shown on fig. 2 of the drawings.

The letters E represent springs, arranged respectively upon the top and bottom sides of the frame of the wash-board, their upper ends being curved, as shown, to provide means for holding the shafts of the rollers in place. These springs E are moved and operated by the set-screws H, and serve as means for adjusting the wringers, and permitting them to be separated by the passage of clothing.

The letters u represent guards affixed by screws to the side pieces of the wash-board, and are removable at will.

The letter S represents what I call the "hand-rest." It consists of a block or cross-bar, screwed to the top of the wash-board frame above the wringer, and serves as a convenient rest for one hand of the operator, while the other is engaged in turning the wringer-crank, and also as means for pressing down the board, and thereby holding it firmly in the tub.

What I claim as my invention, and desire to secure by Letters Patent, is—

A combined washer and wringer, having board A, wringer D, springs E, set-screws H, guards u, hooks c, and hand-rest S, constructed and arranged substantially as specified.

In testimony that I claim the above, I have hereunto subscribed my name, in the presence of two witnesses.

Witnesses:

JAS. S. WIGHTMAN,
A. G. SHATTUCK.
